[57] CLAIM

The ornamental design for a display case, as shown and described.

DESCRIPTION

FIG. 1 is a perspective view showing the front, side and top of my new display case;

FIG. 2 is a side elevational view of the display case showing the transparent cover separated from the base the opposite side being a mirror image thereof; and,

FIG. 3 is a front elevational view of my new display case.

This display case can be used for displaying various articles, for example a pair of children's shoes. The front of the removable transparent cover has a rectangular engraveable plate for identification of the article on display.
